SHOE SEWING MACHINES

Philip H. Randall, Belmont, Mass., assignor to United Shoe Machinery Corporation, Flemington, N. J., a corporation of New Jersey

Application November 22, 1954, Serial No. 470,490

2 Claims. (Cl. 112—52)

The present invention relates to shoe sewing machines of the McKay type having a rotary shoe entering horn for inserting a welt attaching seam in a so-called "American" or "McKay" welt shoe. In certain respects the invention is an improvement over that disclosed in United States Letters Patent No. 2,331,318, granted October 12, 1943, upon application of G. H. Graham.

In the machine of the Graham patent a McKay or American welt shoe is sewed by directing a storm welt having a narrow weather excluding bead into the point of operation of the machine. For this purpose the machine is provided with an edge gage roll acting on the outer surface of the upper in the shoe being sewn along that portion of the upper supported by the edge of the insole, the upper being temporarily attached to the tread surface of the insole by flat lasting. In the machine of the Graham patent the edge gage roll is so formed that it squeezes the bead of the welt forcibly against the portion of the upper supported by the insole to insure an accurate alignment of the bead with the insole edge. In this way the welt is attached in a manner which will prevent gaping of its bead from the upper after the shoe is completed by the addition of an outsole, so that the weather excluding action of the bead is preserved.

For the purpose of giving to a shoe the appearance of a platform sole construction it has been found desirable to attach to a flat lasted shoe a welt having a relatively wide lip or rib with as great a widthwise dimension as the attaching flange on the welt. Such welt is either in the form of a right angle or a T-shaped section and is so constructed that it presses resiliently against the upper at its extreme edge after attachment. For this purpose while the welt is in its relaxed condition before attachment to a shoe the lip is inclined toward the flange on which the attaching means acts. In order to position properly the flange of the welt, on which the attaching means acts, on a shoe it is necessary to flex the lip to more or less degree away from the attaching flange and, in the case of a T-welt, to flex toward the flange to which the outsole is to be secured. After attachment to the shoe the natural resiliency of the welt causes the lip to hug the bulging portion of the shoe upper with a tight weather excluding joint between them. To insure uniform pressure of the lip on the upper it is necessary also to avoid stretching the welt in a lengthwise direction by keeping it free from resistance to easy feeding movement with the shoe during attachment.

The objects of the present invention are to improve a sewing machine of the McKay type in a manner which will enable an angular or T-shaped weather excluding welt to be sewn to a flat lasted shoe without the exercise of exceptional skill or ability on the part of the operator of the machine. A further object is to provide an improved welt guide for a machine of the type referred to, for directing a T-shaped welt to the sewing point in the machine with the parts presented to the sewing point uniformly in proper relationship.

2

To the ends indicated above, one feature of the invention resides in a shoe machine for operating on a welt formed with a flange for attaching it to a shoe and a resilient weather excluding lip extending at an acute angle to the attaching flange to cause it to engage with a uniform yielding action against the bulging upper of the shoe, which machine is provided with the usual attaching and work feeding devices, a rotary shoe entering horn, a presser foot and an edge gage mounted on the presser foot, which machine also is equipped with a slotted guide shaped to fit the flange of the welt and provided with a finger extending from one side of the slot in the guide at an acute angle to the direction of the welt running between the guide and the shoe to bulge the lip of the welt from an acute angular relationship with the attaching flange into an obtuse angular relationship therewith. Preferably, the attaching means comprises stitch forming devices, and the edge gage is in the form of a rotatable roll into contact with whose periphery the lip is wrapped for a substantial distance in advance of the point of operation of the stitch forming devices through the bulging action of the finger on the lip. With such machine the shoe is guided uniformly by engagement of the outer surface of the lip on the welt with the guide roll without imparting excessive frictional resistance to the movement of the welt during feed of the shoe. Accordingly, the welt is applied to a shoe with little, if any, tension and uniform results are insured.

These and other features of the invention, as hereinafter described and claimed, consist in certain novel constructions, combinations, and arrangements of parts which will readily be understood from the following detailed specification taken in connection with the accompanying drawings, in which,

Fig. 1 is a fragmentary view in front elevation of a portion of a shoe sewing machine embodying the present invention, showing its manner of operation on a shoe;

Fig. 2 is a detail perspective view of a short length of welt intended to be operated upon by the machine of Fig. 1;

Fig. 3 is a sectional view taken across a seam inserted by the machine, as seen from the line III—III of Fig. 1;

Fig. 4 is a sectional plan view of certain parts of the machine and shoe being operated upon, looking from the line IV—IV of Fig. 1;

Fig. 5 is a detail view taken from the line V—V of Fig. 1 of the welt guide including a welt of T-section with its lip bulged immediately in advance of the operating point of the machine; and

Fig. 6 is a sectional plan view of a portion of the guide illustrating its lip bulging finger, as seen from the line VI—VI of Fig. 5.

The machine illustrated in the drawing is similar, except as hereinafter described, to that disclosed in United States Letters Patent No. 1,827,321, granted October 13, 1931, upon application of B. T. Leveque and is intended to operate upon the bottom of a flat lasted shoe having an upper 2 overlapping the tread surface of its insole 4. During operation of the machine a T-shaped welt of the construction shown in Fig. 2 is led toward the operating point on a shoe until a flange 6 for attaching the welt to the shoe comes into contact with the portion of the upper which overlaps the insole. The welt also has an outsole securing flange 8 and a resilient weather excluding lip 10 formed at an acute angle with relation to the flange 6. The lip has at its extremity a sharpened feather edge pointed in the same direction as the attaching flange, so that when the welt is attached to the shoe a yielding weather excluding contact is insured throughout the length of the welt between the lip and the bulging surface of the upper.

For attaching the welt, stitch forming, work supporting

3 and feeding devices are provided in the illustrated machine and these devices include a straight hook needle 12, a feed point 14, a rotary shoe entering horn 16, and a presser foot 18 secured to the lower end of a presser foot bar 20 to clamp the work against the tip of the horn. To direct the welt into the sewing point of the machine there is mounted on the presser foot at a position along the line of welt attachment in advance of the point of clamping engagement of the presser foot with the work a slotted guide 22 in the form of a double ended perforated plate shaped at both ends to fit the attaching and outsole securing flanges of the welt, the lip of the welt extending through cuts entering the flange retaining slots also at both ends of the guide plate. To mount the guide on the presser foot a bolt 24 passes through an elongated aperture in the midportion of the guide, through a spacer 26 and an opening in the presser foot 18 into threaded relation with the lower end of the presser foot bar 20. To enable the marginal portions of the upper and insole to be directed accurately into the sewing point the presser foot also has mounted upon it an edge gage roll 28 through which passes a clamp bolt 30 secured within a slot in the presser foot at a position along the line of stitching inserted by the machine opposite the point of needle operation. As thus far described the illustrated machine is the same as that disclosed in the prior patents.

According to the present invention, the slotted and perforated guide plate 22 which directs the welt onto a shoe is located in a position above the level of the shoe bottom in advance of the point of sewing operations, the welt moving downwardly until its attaching flange comes into contact with the marginal portion of the upper which overlaps the tread surface on the insole, and the lip 10 of the welt immediately in advance of the point of clamping engagement of the presser foot on the work is bulged away from its acute angular relationship with the attaching flange 6 into an obtuse angular relationship therewith. By bulging the lip immediately in advance of the sewing point the angular portion of the shoe upper along the edge of the insole is cleared of obstruction to free movement into the apex of the obtuse angle between the lip and the attaching flange without danger of frictional contact by the feather edge on the lip or of possibility that the lip will be folded against the bottom of the shoe and drawn under the attaching flange into line with the stitch forming devices.

To bulge the lip of the welt immediately in advance of the sewing point in the illustrated machine the slotted welt guide 22 has extending beneath the outsole attaching flange of the welt from the rear side of its welt slot in its left end an integral lip deflecting finger 32. The finger 32 has a lip engaging edge which extends at an acute angle to the direction of the welt running between the guide and the point of clamping engagement of the presser foot with the work. The lip is deflected by the finger into contact a substantial distance along the periphery on the roll 28, as best shown in Fig. 4. The lip 10 exerts some pressure against the roll but because the roll is free to rotate the pressure between the lip and the roll does not produce frictional resistance to movement of the welt during work feed. The finger 32 is located a short distance above the bottom of the shoe and so does not interfere objectionably with the clear feeding and positioning movements of the shoe, most of the surfaces of the shoe being curved downwardly away from the finger.

The lip bulging finger 32 on the welt guide is effective in deflecting the lip 10 from an acute angular relationship to the attaching flange 6 on the welt into an acute angular relationship with the outsole securing flange 8, as shown in Fig. 5. For the purpose pointed out the guide may be employed with any type of welt having an attaching flange and an upper engaging lip disposed in normal relaxed condition at an acute angle to each other. While the finger is useful in sewing ordinary leather welt constructed with flange and lip at an acute angle to each other, the greatest benefit is obtained in operating upon welt of

extruded synthetic plastic material, such as Koro seal and other rubber-like substances. The advantage gained in sewing welt constructed from such material is obtained from its resilient action in forming a tight weather excluding joint between the lip and the upper of a shoe. The finger is so shaped that after bulging the lip away from the attaching flange on the welt the lip is allowed to return into firm resilient contact with the shoe upper. Thus, the bulge in the welt lip not only clears the shoe 10 along that portion in advance of the presser foot for free feeding and positioning movements in spite of the lip on the welt but also enables the welt to be carried over the tread surface of the shoe to bring its attaching flange into a fuller more uniformly overlapping relationship with the 15 upper than has been possible with previous guides for similar welt. A welt guide of the construction described also is useful with machines for attaching welt to shoes by cement or by seams other than those formed by thread.

The nature and scope of the invention having been 20 pointed out and a particular embodiment having been described, what is claimed is:

1. A machine for attaching to the bottom of a flat lasted shoe, a welt formed with an attaching flange and a resilient weather excluding lip extending at an acute 25 angle to each other to cause the lip to press yieldingly against the bulging surface of the upper, said machine having attaching and work feeding devices, a rotary shoe entering horn, a presser foot acting to clamp the work against the horn and an edge gage mounted on the presser 30 foot along the line of attachment opposite the point of operation of the attaching devices, in combination with a slotted guide mounted along the line of attachment in advance of the presser foot, shaped to fit the flange of the welt and provided with an integral finger extending from 35 one side of the slot in the guide beneath the attaching flange on the welt and at an acute angle to the direction of the welt running between the guide and the presser foot to bulge the lip on the welt immediately in advance of the point of attachment from an acute angular relationship 40 with the attaching flange at one side of the lip into an obtuse angular relationship with the flange, thus clearing the shoe for free movement in advance of the presser foot.

2. A sewing machine of the McKay type for attaching 45 to the bottom of a flat lasted shoe by through and through stitches a welt formed with an attaching flange and a resilient weather excluding lip extending at an acute angle to each other to cause the lip to be pressed yieldingly into contact with the bulging surface of the upper, said machine having stitch and work feeding devices, a rotary shoe entering horn, a presser foot acting to clamp the work against the horn and an edge gage roll mounted on the 50 presser foot at a position along the line of stitching opposite the point of operation of the stitch forming devices, in combination with a slotted guide mounted on the presser foot at a position along the line of attachment in advance of the point of clamping engagement of the presser foot with the work, shaped to fit the attaching flange on the welt and provided with a finger extending 55 beneath the attaching flange on the welt from one side of the slot in the guide toward the edge gage roll to a position immediately in advance of the point of engagement of the presser foot with the work to bulge the lip on the welt away from its acute 60 angular relationship with the attaching flange and to wrap it for a substantial distance about the periphery of the edge gage roll, thus clearing the shoe for free movement in advance of the presser foot.
